REVOLVABLE ELECTRIC PLUG

Filed Jan. 11, 1939

Fig. 1.

UNITED STATES PATENT OFFICE

2,248,759

REVOLVABLE ELECTRIC PLUG

Joseph J. Hollander, Chicago, Ill.

Application January 11, 1939, Serial No. 250,313

5 Claims. (Cl. 173—324)

The object of this invention is to provide an electrical plug of the revolvable type capable of efficiently giving an electrical connection regardless of the rotatory disposition of the plug and the connecting wires thereto.

It is a further object of this invention to provide a revolvable plug of the character described which will be simple in construction and operation and be capable of cheap production in large quantities, being highly efficient in carrying out the purpose for which it is designed.

Heretofore, plugs and electrical connections of the general nature of this invention have been invariably complicated and have consequently given unsatisfactory service besides being difficult to repair and cumbersome to use. It is a further object of this invention to eliminate the difficulties occasioned by prior devices by providing for an extremely simple and yet highly efficient revolvable socket of the character described.

With the foregoing and other objects in view, which will appear as the description proceeds, the invention consists in certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing, a preferred embodiment thereof, from an inspection of which, when considered in connection with the following description of my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is an elevational view of an embodiment of the present invention installed in the side of a wall as an outlet;

Fig. 2 is a side elevational view of the embodiment of the present device shown in Fig. 1;

Fig. 3 is a sectional view taken along the line 3—3 of Fig. 1 and in the direction of the corresponding arrows;

Fig. 4 is a sectional view taken along the line 4—4 of Fig. 3 and in the direction of the arrows.

Referring to specific constructional details, the reference character 10 designates the face plate of an embodiment of the present invention, provided with countersunk holes 11 for the reception 5 of screws 12 or the like for attaching the plate 10 to a wall 13. Said plate 10 is provided centrally thereof with an opening 14, said opening being of larger diameter than the socket designated generally by the character 15 which projects therethrough.

The socket 15 is formed of an insulating material such as Bakelite or the like, and consists of two halves, 16 and 17, adapted to be held together by screws 18 or other fastening means, 15 forming the socket 15 as a substantial cylindrical member. Said socket is provided with recesses 19 and 20 leading to the interior thereof from the front face 21, within which are disposed resilient contact members 22 and 23. Said resilient contact members 22 and 23 are adapted to be maintained within the recesses 19 and 20 when the halves 16 and 17 are in operative assembly by reason of the reduced diameter portions 24 and 25 forming shoulders 26 and 27 preventing the longitudinal movement of said contact members.

The recesses 19 and 20 and the resilient contact members therein are adapted to receive and retain the prongs of a common male electrical plug 28 to permit wires 29 attached to said plug to freely rotate with said plug and socket 15, preventing tangling, twisting, etc. For this reason, the socket member 15 is rotatably attached to the bracket 30 in a manner to be hereinafter described.

35 The contact member 22 is connected by means of a metallic screw 31 threading a portion 32 thereof, to a contact member 33. Said contact member 33 extends into a conical recess 35 formed in the central portion of said socket member 15 on the face 34 thereof for a purpose to be described. Said contact member 33 is formed from resilient metal and is adapted to normally be urged to the right as viewed in Fig. 3.

40 The plug member 15 is provided with a reduced diameter portion 36 for the purpose of forming the shoulder 37 against which is disposed and fixed an annular ring 38 of conducting material. Said ring 38 is connected to the contact 23 by means of a metallic screw 39 extending through said ring and into a threaded portion 40 provided on said resilient contact member 23.

45 It will be seen from the above description that an electrical path has been established to the annular ring 38 and the contact member 33 from

the resilient contact members 22 and 23, respectively.

The plug 15 is rotatively attached to the bracket 30 by means of the pin 41. Said bracket 30 is of substantially U-shaped construction and its legs 42 and 43 are attached at the ends 44 and 45 thereof to the rear of the plate 10 by means of recessing and riveting as shown at 46, or by other means. The pin 41 is provided at one end thereof with a head 47, which is maintained within a recess 48 sunken in the face 21 of the plug member 15 centrally thereof. The other end of the pin 41 is fixedly attached to the bracket 30 by reason of its being threaded as at 49 for the reception of the nut 50. Intermediate the ends of said pin 41, a shoulder 51 is provided at the junction of the body of the pin 41 with a reduced diameter portion 52. A conical conducting member 53 abuts against this shoulder 51, extending into the recess 35 and wiping the resilient contact member 33. Between said conical member and said nut 50 are maintained in fixed relation, respectively, a metallic washer 54, a large washer 55 of insulating material, a smaller washer 56 of insulating material, serving to space the reduced diameter portion 52 of said pin 41 from an opening provided therefore in the bracket 30, another washer 55, and two metallic washers 57 between which is fixed the electrical conductor 58 of the wire 59.

It will be noted that the pin body 41 is loosely maintained in the opening provided therefor in the plug member 15, allowing the plug member to rotate thereon. Also, note that any play resulting in assembly of the device is taken up by reason of the resilience of the contact member 33 urging the plug member 15 to the left as viewed in Fig. 3.

The leg 42 of the bracket 30 has mounted thereon a resilient contact member 60 which serves to wipe the annular ring 38 as the plug member 15 rotates, constantly maintaining electrical contact therewith. Said contact member is fixedly attached to, but insulated from the bracket leg 42, as designated generally at 61, in a manner similar to the fixation of the pin 41 to the bracket 30 and is connected to provide an electric path to the lead wire 62.

It will now be apparent how an electrical plug 28 could be inserted into a wall outlet in which the present invention has been embodied, and maintain electrical contact with the main line regardless of the rotatory disposition of the plug, without twisting of the lead wires thereto.

While the illustrated embodiment has specifically disclosed attaching means for the pin 41 and the resilient contact member 60 to be fixed to and insulated from the bracket 30, it is obvious that other means could be employed. The inventor does not wish to limit himself to the specific means described, but rather desires to receive protection for the generic constructional principles.

The plug member 15 may be formed with recessed portions within the same, as shown at 63, to reduce the weight and the amount of material thereof.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide

variation within the purview of my invention as defined in the appended claims.

I claim:

1. In a device of the character described, the combination of a substantially U-shaped bracket, an electrical plug member provided with contacts within recesses provided therein for the reception of male prongs, said electrical plug member being rotatably attached to and insulated from said bracket and being spaced between the arms thereof, an annular ring about said plug member establishing contact with a contact member fixed to and insulated from said bracket, a pin upon which said plug member is mounted for effecting said rotatable attachment, said annular ring being electrically connected with one of the recessed contacts, and said pin member being electrically connected with a second of said recessed contacts, the contact member of said bracket being attachable to one lead of an electric power line, said pin member being adapted to be attached to the other lead of said line.

2. In a device of the character described, the combination of a frame-like bracket, an electrical plug member provided with contacts within recesses provided therein for the reception of male prongs, said electrical plug member being rotatably attached to and insulated from said bracket and being substantially spaced within same, an annular ring about said plug member establishing contact with a resilient contact member fixed to and insulated from said bracket, a pin upon which said plug member is mounted for effecting said rotatable attachment, said ring being electrically connected with one of said contacts within one of said recesses, and said pin being electrically connected with the other of said contacts within said recesses.

3. In a device of the character described, an electrical plug provided with recesses within which are disposed contacts on one face of said plug, a bracket, pin means fixed to and electrically insulated from said bracket extending through said plug and rotatably attaching said plug to said bracket with the sides thereof substantially spaced from said bracket, means provided on said pin means for entering a recess on the opposite face of said plug and establishing an electrical path between a contact member within said recess and an electrical conductor attached to said pin means, an annular electrical conducting ring about said plug, contact means insulatedly attached to said bracket and riding upon said ring and establishing electrical contact between said ring and a second electrical conductor, said contacts within said recesses of said first-mentioned face of said plug being respectively electrically connected with said annular ring and said contact within said recess on said second-mentioned face of said plug.

4. In a device of the character described, an electrical plug rotatably mounted upon a bracket by means of a pin member fixedly attached to and electrically insulated from said bracket, said plug being of substantially cylindrical shape and adapted to rotate on the axis of the cylinder, said bracket having portions thereof extending parallel to the sides of said plug and being spaced therefrom, recesses within the front face of said plug, contact members adapted to receive male prongs contained within said recesses, an annular ring of conducting material disposed about the plug, and means for establishing electrical connection between the recessed contacts and

external conductors, including electrical connection between one of said recessed contacts and said ring, a central conical recess formed on the rear face of said plug, a spring contact member disposed upon the inner surface of said conical recess and adapted to establish contact with one of said external conductors, and electrical connection between another of said recessed contacts and said spring contact member.

5. In a device of the character described, an 10 electrical plug rotatably mounted upon a bracket by means of a pin member fixedly attached to and electrically insulated from said bracket, said plug being of substantially cylindrical shape and adapted to rotate on the axis of the cylinder, said 15 bracket having portions thereof extending parallel to the sides of said plug and being spaced therefrom, recesses within the front face of said plug, contact members adapted to receive male prongs contained within said recesses, an an- 20

nular ring of conducting material disposed about the plug, and means for establishing electrical connection between the recessed contacts and external conductors, including electrical connection 5 between one of said recessed contacts and said ring, a central conical recess formed on the rear face of said plug, a spring contact member disposed upon the inner surface of said conical recess, conical shaped conducting means fixedly attached to said pin member and adapted to be disposed within said conical recess to permit the wiping thereof by said spring contact member on rotation of said plug, electrical connection being provided between said spring contact member and another of said recessed contacts, and electrical connection being provided between said conical shaped conducting means and one of said external conductors by means of said pin member.

JOSEPH J. HOLLANDER.
